[57] **CLAIM**

The design for magnetic wheel spiral toy, substantially as shown and described.

DESCRIPTION

FIG. 1 is a front elevation view of a magnetic wheel toy showing my new design, the rear elevation view being a mirror image, the magnetic wheel shown in broken lines for illustrative purposes only and forming no part of the claimed design;

FIG. 2 is a right side elevation view with the left elevation view being a mirror image thereof; and,

FIG. 3 is a top plan view with the bottom plan view being a mirror image thereof.
